US0D1107264S

(12) **United States Design Patent** (10) Patent No.: **US D1,107,264 S**
(45) Date of Patent: **** Dec. 23, 2025**

(54) **INSULATED FORM**

(71) Applicant: **Haim Bar**, Beit Hanan (IL)

(72) Inventor: **Haim Bar**, Beit Hanan (IL)

(**) Term: **15 Years**

(21) Appl. No.: **35/517,939**

(22) Filed: **Jul. 11, 2023**

(80) **Hague Agreement Data**

Int. Filing Date: **Jul. 11, 2023**

Int. Reg. No.: **DM/230440**

Int. Reg. Date: **Jul. 11, 2023**

Int. Reg. Pub. Date: **Jul. 28, 2023**

(51) **LOC (15) Cl. 25-01**

(52) **U.S. Cl.**

USPC **D25/124**
